Inventor

David H. Rassner

UNITED STATES PATENT OFFICE.

DAVID H. RASSNER, OF PERU, INDIANA.

LINOLEUM CUTTER.

Application filed November 20, 1922. Serial No. 602,101.

To all whom it may concern:

Be it known that I, DAVID H. RASSNER, a citizen of the United States, residing at Peru, in the county of Miami and State of Indiana, have invented certain new and useful Improvements in Linoleum Cutters; and I do declare the following to be a full, clear, and exact description of the invention, such as will enable others skilled in the art to 10 which it appertains to make and use the same.

My invention relates to hand operated cutters for sheet material and has reference more particularly to a device of this character which is intended primarily for cutting linoleum, the object being to provide an extremely simple and inexpensive, yet a highly advantageous tool which may be effectively used in laying linoleum, regardless of 20 the character of the numerous cuts which are necessarily made.

With the foregoing in view, the invention resides in the novel subject matter herein-after described and claimed, the description 25 being supplemented by the accompanying drawing:—

Figure 1 is a side elevation of a linoleum cutter constructed in accordance with my invention.

Fig. 2 is an enlarged longitudinal sectional view through the front end of the cutter.

Fig. 3 is a transverse section on line 3—3 of Fig. 2.

In the drawings above briefly described, 35 the numeral 1 designates a preferably straight metal shank having a suitable hand grip 2 at its rear end, while its front end is formed with a longitudinal slot 3 which opens at opposite sides of the shank and is closed at both ends. A suitable blade 4 is 40 removably received in the slot 3 and contacts with the front wall of said slot, while the rear edge of said blade is engaged by a tubular blade holder which is threaded upon 45 the shank 1. This blade holder preferably consists of a front section 5 which is merely slidable upon the shank 1, and a rear knurled section 5' which is threaded upon said shank.

It will be seen that when the holder is tightened, 50 the blade will be effectively held in operative relation with the shank 1, but when said holder is loosened, the blade may easily be removed for sharpening or to permit the substitution of a new blade.

The front edge of the blade 4 is preferably 55 provided with a central notch 6 receiving the front end wall of the slot 3, which wall is shown of V-shape as indicated by the numeral 7. The rear edge of the blade 4 is formed with a central projection 8 received in the front end of the section 5 of the blade holder. By employing these details of construction, it will be seen that the blade is positively held against lateral shifting 60 within the slot. 65

In the preferred form of construction, the front end of the blade 4 is formed with two cutting edges 9, both of which are at an obtuse angle to the axis of the shank 1, whereby effective cutting may be performed by 70 pushing the tool. In order that the cutting may also be accomplished by pulling the tool whenever necessary, the rear end of the blade 4 is provided with a pair of hook-like cutting edges 10. During the operation of 75 covering a floor with linoleum or the like, it is necessary at times to use one of the cutting edges 9 and at other times to employ the edge 10. Similarly, in order to complete a single cut, it is often necessary to use 80 one of the cutting edges for a portion of this cut and the other edge to complete the same.

Excellent results have been obtained from the details herein disclosed and these details are therefore preferably followed. I wish 85 it understood however, that within the scope of the invention as claimed, numerous minor changes may be made.

I claim:—

A device of the class described comprising 90 a shank having a hand-grip at its rear end and a longitudinal slot in its front end, said slot being closed at both ends, a blade removably received in said slot and contacting with the front end thereof, the front 95 edge of said blade being formed with a notch receiving the front end wall of the slot, and the rear edge of said blade being formed with a projection, and a tubular blade-holder threaded on said shank, the 100 projection on said blade being received in the outer end of said holder.

In testimony whereof I have hereunto affixed my signature.

DAVID H. RASSNER.
